UNITED STATES PATENT OFFICE.

CHARLES HENRY FISH, OF MANCHESTER, NEW HAMPSHIRE.

SULPHUR-FURNACE.

SPECIFICATION forming part of Letters Patent No. 451,651, dated May 5, 1891.

Application filed December 8, 1890. Serial No. 373,933. (No model.)

To all whom it may concern:

Be it known that I, CHARLES HENRY FISH, of Manchester, county of Hillsborough, State of New Hampshire, have invented an Improvement in Furnaces for Burning Sulphur, of which the following description, in connection with the accompanying drawings, is a specification, like letters on the drawings representing like parts.

10 My invention relates to a furnace for burning sulphur for the production of sulphur fumes to be used in making sulphuric acid. Furnaces for this purpose as heretofore made consist of a long horizontal tight chamber, 15 which may be made of cast-iron, and which has at one end a feed-door through which the sulphur to be burned is introduced and at the other or rear end an outlet-opening connected with a pipe or duct through which the 20 fumes produced by burning the sulphur are led away. These furnaces have heretofore been made tight at their rear or discharge ends, and consequently the accumulations or dirt or ash arising from the combustion of 25 the sulphur, which usually contains more or less impurities, have to be withdrawn through the feed-door at the front of the furnace, an operation which interferes with the proper burning of the sulphur and is also attended 30 by a considerable waste of the sulphur which has been previously introduced into the furnace and partly burned.

The object of the present invention is to produce a furnace having means for the removal of the ash or accumulation or dirt without interfering with the burning of the sulphur and also without producing any waste. To accomplish this result, the furnace embodying this invention is provided with an 40 ash-receptacle at the rear of the furnace proper, in which the sulphur is burned, into which receptacle the dirt or ash is carried during the operation of the furnace, and from which the said accumulated ash may be removed from time to time through a suitable opening provided with a cover or door. By this construction the furnace may be fed with fresh sulphur from time to time at the front end, the previously-introduced and partially-consumed sulphur being gradually carried toward the rear end and the dirt or ash being carried along with it and delivered

from the rear end into the ash-receptacle, from which it is removed from time to time as it accumulates in sufficient quantities. 55

Figure 1 is a side elevation of a furnace for burning sulphur embodying this invention; Fig. 2, a longitudinal section thereof; Fig. 3, a front end elevation; Fig. 4, a rear end elevation, and Fig. 5 a transverse vertical section.

The main portion or body *a* of the furnace may be of usual construction, being a long substantially horizontal chamber or drum having an arched top and flat bottom, which latter is depressed for the greater portion of its length below the level of the openings at the ends of the drum, as best shown in Fig. 2, the said bottom rising by gradual inclines *a*² *a*³ toward the said openings. 70

At the forward end the furnace is provided with a mouth-piece *b*, having the feed-door *c*, which rests against an inclined seat, as shown, and is provided with a lifting cord or chain *c*², passing over pulleys *c*³ and provided with a counter-weight *c*⁴, to enable it to be raised for the purpose of opening the front of the furnace to permit the sulphur to be fed in. The said door *c* has an opening *c*⁵ (see Fig. 3) for the admission of air to support the combustion of the sulphur, which when ignited melts and burns on the floor of the furnace in a semi-fluid condition, being prevented from flowing out by the inclines *a*² *a*³ near the ends of the floor. 80

The furnace is supported in a slightly-inclined position, with the rear or outlet end a little below the level of the mouth-piece *b*, through which the fuel is fed, as shown by reference to the horizontal dotted line, Fig. 2, 90 so as to give the fuel a slight tendency to move from the front toward the rear end of the furnace, and as the sulphur burns, the sand, dust, or earthy impurities, constituting a kind of ash, will become separated from the sulphur, which is itself entirely consumed. The ash resulting from the impurities has to be removed from time to time as it accumulates, and in furnaces of this kind as heretofore constructed it has had to be removed 100 from the front or feeding end of the furnace, thus necessitating the keeping of the feed-door *c* open, and thereby greatly interfering with the proper burning of the sulphur, and

also involving a considerable waste of the sulphur, which is withdrawn with the ash during the cleaning process. In order to obviate this objection, the furnace herein shown is provided with a supplemental chamber *d*, connected with the rear end of the furnace and provided with the outlet-opening *d*², to which the duct for carrying away the fumes is connected. The main body of the chamber *d* is on the level with the outlet-opening of the main body *a* of the furnace, but it is provided at its bottom with a depressed chamber or receptacle *e*, having an opening, shown in this instance as made at the end, which is provided with a removable cover *e*², which normally stands in position to close the said opening, and thus prevent communication between the inside of the supplementary chamber *d* and the external air. The supplementary chamber *d* with the receptacle *e* receives the ash, which is gradually separated from the sulphur as the latter is consumed and is pushed to the rearward in the furnace, said ash collecting in the receptacle *e*, from which it may be removed from time to time, as required, by opening the cover *e*² and raking or drawing out the ash.

In the operation of the furnace the fresh sulphur is introduced as required through the door *c* and tends to displace the sulphur that is already burning, which thus gradually moves to the rearward in proportion as the fresh material is fed in at the front, the ash being carried along toward the rear and up the incline *a*³ into the chamber *d*, where it settles in the receptacle *e* substantially free from sulphur, and from which it is removed

from time to time, as before stated. By this construction the feed-door *c* does not have to be kept open for any great length of time, it being necessary to open it only while the new material is being introduced and the previously partially-consumed sulphur and ash pushed to the rear, the contents of the furnace always moving from the front to the rear of the furnace and never having a retrograde movement, as is the case in furnaces of this kind as heretofore made and operated.

The body *a* of the furnace is set in the usual water-pan *f*, and is kept cool by water dripping upon it from sprinkling-pipes in the usual manner.

While the furnace has been described as employed for burning sulphur, it is obvious that the same construction is useful wherever any material having the same characteristics is to be burned or ignited.

I claim—

The main body of the furnace, having a feed-door at one end and a supplemental chamber provided with an ash-receptacle at its other end, the floor of said furnace being depressed below its end portions and said ash-receptacle having an outlet-opening and cover therefor, substantially as and for the purpose described.

In testimony whereof I have signed my name to this specification in the presence of two subscribing witnesses.

CHARLES HENRY FISH.
